UNITED STATES PATENT OFFICE

JOHN B. TEESDALE, OF GRAND RAPIDS, MICHIGAN

ROTARY PUMP

Application filed May 6, 1929. Serial No. 360,864.

The present invention relates to pumps; and its object is, generally, to provide a rotary pump improved in respects hereinafter appearing; and more particularly, to provide such a pump having a gate member movable into and out of fitting contact with the pump's rotor piston, and inlet and outlet ports so arranged relatively to the gate member that the same may be moved out of such contact by a certain degree of pressure thereon exerted by the pumped fluid; and further, to provide means for adjusting the degree of such required pressure; and further, to provide in such a pump, a gate member properly balanced between fluid pressures on its opposite sides; and further, to provide in such a pump improved and effectively positioned ports; and further to provide in such a pump improved means for returning to the pump fluid leaking therefrom into its bearings.

These and any other objects hereinafter appearing are attained by, and the invention finds preferable embodiment in, the pump hereinafter particularly described in the body of this specification and illustrated by the accompanying drawings, in which:

Figure 1 is a side view of a rotary pump, certain parts being shown in axial section taken on line 1—1 of Figure 2;

Figure 2 is a transaxial sectional view thereof taken on line 2—2 of Figure 1;

Figure 3 is a side view of the same viewed at right angles to the direction in which Figure 1 is viewed, certain parts being shown in axial section;

Figure 4 is a front view of the same;

Figure 5 is a view of a rear cap, the rotor piston's shaft being shown in transverse section; and

Figure 6 is a transaxial sectional view of a rotary pump showing a modified construction of certain parts.

The rotary pump illustrated by these drawings has a body comprising a rear portion 1, an intermediate portion 2 and a front portion or cap 3, these parts being securely joined by screws 4 passing through portions 2 and 3 and threaded in portion 1. This body thus formed has a cross-sectionally round chamber 5 and a fluid passage 6 communicating there-

with and having an inlet port 7 for the fluid being drawn into the pump and an outlet port 8 through which the fluid is discharged from the pump.

A rotor piston 9 in the chamber 5 is driven by suitable power applied to its shaft 10 turning in a rotary bearing 12 in the sleeve 11 held in the bore 13 of portion 1 of the body. This piston is cross-sectionally round, is of less diameter than the chamber and its axis of rotation (the axis of its shaft 10) is offset from the axis of the chamber as shown.

A gate 14 is swingably movable in said passage, one end of the gate having a journal portion 15 turning in the rotary bearing 16 formed in the body portion 2 adjacent the passage 1. Thus mounted and swingable, the gate's free end 17 extending into the chamber 5 fittingly contacts the side of the rotor piston and separates the passage 6 into a part 18 into which the fluid enters through the inlet port 7 and a part 19 through which the pumped fluid passes from the chamber 5 and into the outlet or discharge port 8. This gate is pressed into fitting contact with the rotor piston by a suitable spring 20 in an opening 21 through the body portion 2 and pressing between the slideable head 22 (contacting the gate) and the screw plug 23 which may be turned to regulate the tension of said spring.

It will be seen that when the piston is rotated the fluid is drawn through the inlet port 7 and into part 18 of the passage 6 (at one side of the gate) and thence into the chamber 5, and is expelled from chamber 5 into part 19 of said passage (at the opposite side of the gate) being discharged from the pump through the outlet port 8. Furthermore: It will also be seen that when the piston is being rotated faster than a predetermined speed and more fluid is thus being pumped than the predetermined amount, the pressure of the fluid issuing from chamber 5 into part 19 of passage 6 presses upon that side 25 of the gate which forms the wall of said part 19 with such force as to swing the gate and move its free end 17 out of contact with the piston, such swinging movement of the gate compressing the spring 20 further than the degree to which the turned position

100

of the screw plug 23 has tensioned it, such turned position of the plug measuring the amount of fluid desired to be pumped from the source of supply during a certain time; 5 and it will be seen that, when the pre-adjusted tension of the spring is thus increased by the increased pressure of fluid being pumped at the time, and the free end 17 of the gate having been thus moved out of contact with the piston, a portion only of the fluid in part 19 of the passage 6 is discharged through the outlet port 8, the rest of the fluid being moved past the end 17 of the gate and driven round and round in the chamber 5 by the piston's rotation; and also, when the outlet 8 or the pipe leading therefrom is closed by a valve or otherwise, all the fluid entering the pump is thus driven round and round in the chamber. It will be thus understood that when the tension of spring 20 is adjusted as desired, the amount of fluid delivered from the pump may be governed correspondingly; and that, if the delivery from the pump be entirely shut off, no harm will result from the continued 25 rotation of the piston.

In the modified construction shown in Figure 6, the middle portion 2¹ of the body of the pump contains operating parts similar to those seen in the other views; but in Figure 30 6, the gate 14¹ is shorter and the parts 18¹ and 19¹ of the passage 6¹ are so positioned and related to the gate 14¹ that the gate is fairly evenly balanced between fluid pressures on its opposite sides, and therefore the spring 20 35 is under only slight tension during the normal pumping operation. In this view, the outlet port 8¹ from part 19¹ of passage 6¹ extends at 26 through the side of the gate and then at 27 in the axial direction of the gate's 40 swinging movement to a vent to the outside of the pump's body.

In Figures 2 and 3 a small passage 28 is indicated extending from an annular groove 29 in the inner surface of sleeve 11 to part 45 18 of passage 6 adjacent the inlet port 7. Fluid leaking from the chamber 5 along the piston's shaft 10 is thus drawn by the pumping operation again into this passage 6 and into chamber 5.

50 The present invention involves a pump structure resembling that shown in my pending application Serial No. 304,592 filed September 7, 1928, but is an improvement as above indicated thereover.

55 The invention being intended to be pointed out in the claims, is not to be limited to or by details of construction of any particular embodiment thereof illustrated by the drawings or hereinbefore described.

60 I claim:

1. In a pump of the character described: a body having a cross-sectionally round chamber and a passage communicating therewith; a rotor piston in the chamber; a gate in the 65 passage movable into and out of fitting con-

tact with the piston; an inlet port to the passage at one side of the gate; an outlet port from the passage at the opposite side of the gate admitting pumped fluid into the passage and pressing directly on the gate in the direction tending to move the same out of its said contact with the piston; means for normally holding the gate in contact with the piston.

2. In a pump of the character described: 75 a body having a cross-sectionally round chamber and a passage communicating therewith; a rotor piston in the chamber; a gate in the passage movable into and out of fitting contact with the piston; an inlet port to the passage at one side of the gate; an outlet port from the passage at the opposite side of the gate admitting pumped fluid into the passage and pressing directly on the gate in the direction tending to move the same out of its said contact with the piston; a spring 80 urging the gate into its said contact with the piston.

3. In a pump of the character described: 90 a body having a cross-sectionally round chamber and a passage communicating therewith; a rotor piston in the chamber; a gate in the passage movable into and out of fitting contact with the piston; an inlet port to the passage at one side of the gate; an outlet port from the passage at the opposite side of the gate admitting pumped fluid into the passage and pressing directly on the gate in the direction tending to move the same out of its said contact with the piston; a spring 95 urging the gate into its said contact with the piston; means for regulating the tension of the spring.

4. In a pump of the character described: 100 a body having a cross-sectionally round chamber and a passage communicating therewith; a rotor piston in the chamber; a pivotally mounted gate in the passage swingable into and out of fitting contact with the piston; an inlet port to the passage at one side 105 of the gate; an outlet port from the passage at the opposite side of the gate admitting pumped fluid into the passage and pressing directly on the gate in the direction tending to swing the same out of its said contact with the piston; means for normally holding the gate in contact with the piston.

5. In a pump of the character described: 115 a body having a cross-sectionally round chamber and a passage communicating therewith; a rotor piston in the chamber; a pivotally mounted gate in the passage swingable into and out of fitting contact with the piston; an inlet port to the passage at one side 120 of the gate; an outlet port from the passage at the opposite side of the gate admitting pumped fluid into the passage and pressing directly on the gate in the direction tending to swing the same out of its said contact with the piston.

the piston; a spring urging the gate into its said contact with the piston.

6. In a pump of the character described: a body having a cross-sectionally round chamber and a passage communicating therewith; a rotor piston in the chamber; a pivotally mounted gate in the passage swingable into and out of fitting contact with the piston; an inlet port to the passage at one side of the 10 gate; an outlet port from the passage at the opposite side of the gate admitting pumped fluid into the passage and pressing directly on the gate in the direction tending to swing the same out of its said contact with the piston; a spring urging the gate into its said contact with the piston; means for regulating the tension of the spring.

7. In a pump of the character described: a body having a cross-sectionally round 20 chamber and a passage communicating therewith, and having also a rotary bearing; a rotor piston in the chamber; a gate in the passage having a journal portion turnable in said bearing, the gate being swingable into and 25 out of fitting contact with the piston; inlet and outlet ports to and from the passage at opposite sides respectively of the gate, one of said ports extending through the gate.

In testimony whereof I have hereunto set 30 my hand at Grand Rapids, Michigan, this 1st day of May, 1929.

JOHN B. TEESDALE.
